FIG. 2 is a rear elevational view of the first embodiment;

FIG. 3 is a right side elevational view of the first embodiment;

FIG. 4 is a left side elevational view of the first embodiment;

FIG. 5 is a top plan view of the first embodiment;

FIG. 6 is a bottom plan view of the first embodiment;

FIG. 7 is a sectional view of the first embodiment taken in the direction of line 7-7 of FIG. 2;

FIG. 8 is a sectional view of the first embodiment taken in the direction of line 8-8 of FIG. 2;

FIG. 9 is a top, front, right side perspective view of the first embodiment;

FIG. 10 is a top, rear, right side perspective view of the first embodiment;

FIG. 11 is a top, front, right side perspective view of the first embodiment, including additional environmental subject matter shown in broken lines;

FIG. 12 is a rear elevational view of the case for electronic device showing our new design according to a second embodiment, the second embodiment being identical to the first embodiment except that the second embodiment has a break between left and right portions thereof as indicated in FIG. 12; and,

FIG. 13 is a rear elevational view of the case for electronic device showing our new design according to a third embodiment, the third embodiment being identical to the first embodiment except that the third embodiment has a break between top and bottom portions thereof as indicated in FIG. 13.

The broken lines in FIGS. 1-10 form no part of the first embodiment of the claimed design and illustrate portions of the case for electronic device that form no part of the first embodiment of the claimed design.

The broken lines in FIG. 11 form no part of the first embodiment of the claimed design and illustrate portions of the case for electronic device and other environmental subject matter that form no part of the first embodiment of the claimed design.
